ATTORNEYS

UNITED STATES PATENT OFFICE.

OTIS A. MYGATT, OF NEW YORK, N. Y.

DESIGN FOR A SHADE OR REFLECTOR OR SIMILAR ARTICLE.

40,659.

Specification for Design.

Patented Apr. 26, 1910.

Application filed June 5, 1908. Serial No. 436,995. Term of patent 14 years.

To all whom it may concern:

Be it known that I, OTIS A. MYGATT, a citizen of the United States, residing at New York, in the county of New York and State of New York, have invented a new, original, and ornamental Design for a Shade or Reflector or Similar Article, of which the following is a specification, reference being had to the accompanying drawing, forming part thereof.

My design is a glass shade or reflector having substantially the shape shown in the accompanying drawing, and provided with exterior prisms lying substantially in the planes intersecting the longitudinal axis of the shade.

Figure 1 is a bottom plan view of a shade or reflector, or similar article embodying my design. Fig. 2 is a side elevation of the same.

When a shade made in accordance with my invention is viewed from below it gives the appearance of a central brilliantly illuminated ring marked with lines radiating from the central axis of the shade, surrounded by a darker circular portion which appears to frame the brighter interior portion. This varying illumination of the shade is indicated in Fig. 1 although it is impossible to fully illustrate in a drawing the effect obtained from my design.

I claim—

The ornamental design for a shade or reflector, or similar article, as shown and described.

OTIS A. MYGATT.
